[57] CLAIM

The ornamental design for a semiconductor wafer support, as shown and described.

DESCRIPTION

FIG. 1 is a front and upper right perspective view of a semiconductor wafer support showing our new design; FIG. 2 is a front and lower left perspective view thereof;

FIG. 3 is a front elevational view thereof;

FIG. 4 is a left side elevational view thereof, the right side elevational view and the rear elevational view being the same;

FIG. 5 is a top plan view thereof;

FIG. 6 is a bottom plan view thereof; and,

FIG. 7 is a top plan view of a second embodiment of a semiconductor wafer support, all other views being the same as the first embodiment except for the four apertures seen on the top and bottom.
